UNITED STATES PATENT OFFICE.

EDWARD L. ADREON, JR., OF ST. LOUIS, MISSOURI.

TIE-PLATE.

1,073,011.

Specification of Letters Patent. Patented Sept. 9, 1913.

Application filed June 6, 1910. Serial No. 565,819.

To all whom it may concern:

Be it known that I, EDWARD L. ADREON, Jr., a citizen of the United States, and resident of St. Louis, Missouri, have invented 5 certain new and useful Improvements in Tie-Plates, of which the following is a specification containing a full, clear, and exact description, reference being had to the accompanying drawings, forming a part 10 hereof.

My invention relates to tie plates, and the object of my invention is to construct a tie plate having a rigid bearing for the spike.

A further object of my invention is to 15 construct my tie plate by rolling or pressing a number of the same from a single piece of material and then shearing the plates from said piece of material in the widths desired without waste.

20 For the above purposes, my invention consists in certain novel features of construction and arrangement of parts which will be hereinafter more fully set forth, pointed out in the claims and illustrated in the accompanying drawings, in which:

Figure 1 is a top plan view of a number of the plates formed from a single piece of material; Fig. 2 is a top plan view of one of the plates prepared ready for use; Fig. 30 3 is a section taken on the line 3—3 of Fig. 2; Fig. 4 is a view, partly in section, illustrating a center punch mark for a spike opening through one of the projections; and Fig. 5 is a fragmental plan view showing 35 an ordinary spike head in place.

In carrying out my invention I take a single piece of material and roll or stamp it by any suitable rolling or stamping means and in the desired length. By rolling or 40 stamping, I form on the rail bearing surface of the plate a shoulder for the edge of the base of the rail, and integral with said shoulder a series of projections arising from the top surface of the plate, which 45 projections, as illustrated in Figs. 1, 2 and 3, are formed integral with the shoulders of the rail bearing surface of the plate. The projections on one side of the plate are staggered or off-set in relation to the 50 projections formed on the opposite side of the plate. By doing this, the plate is more readily and perfectly rolled, because at all times during the operation of rolling there is substantially an equal amount of material 55 beneath the roll. However, this staggered or off-set relation of the projections would

not be of any advantage if the plate was stamped or cast. However, it is highly advantageous if the plate is rolled. After the plate has been rolled, tie plates may be 60 sheared therefrom in any widths desired without waste. In Fig. 1 I have shown in dotted lines the points where a plate may be sheared.

Having described in a general way the 65 method, I will now proceed to describe the construction of the individual tie plates, reference being had to Fig. 2 as the preferred form.

1 indicates the rail bearing surface of the 70 tie plate, and formed thereon are oppositely disposed shoulders 2 and 3 for the alinement of the base of the rail. Formed integral with the shoulder 2 is a series of projections 4, 5, 6, 7 and 8, and formed integral 75 with the shoulder 3 is a series of projections 9, 10, 11 and 12. These shoulders are, as heretofore stated, struck up or formed on the top surface of the plate by rolling or stamping, and likewise, the series of projections are formed. These projections constitute one of the parts of my invention, for the reason that when a spike opening is formed through the plate through this projection a rigid bearing is formed for the 80 spike.

In Fig. 2 I have illustrated spike openings formed through the plate and through some of these projections. Such openings are intended for screw spikes, and any number of 90 openings can be formed in each plate, as desired. These openings are formed by being punched or drilled through the plate and the projections. They also may occupy any position relative to the shoulders. 95

In Fig. 2 I have illustrated the openings as set back from the shoulder 3, and also the openings as projecting slightly beyond the shoulder 2. When they are completely set back from the shoulder, as illustrated 100 in the left hand side of Fig. 2, all wear is received by the shoulder 3, and when the openings project beyond the shoulder 2, as illustrated in the right hand side of Fig. 2, the spikes receive part of the wear and act 105 to wedge the base of the rail against the shoulder 3. In practice, it is more practical to force the base of a rail against the outside shoulder of the tie plate. By this arrangement of spike openings a further advantage 110 follows after installation, especially where the plate is applied to the rail at curves in

which instance the plate may be reversed, placing the shoulder 3 against the outside edge of the rail, which narrows the gage and compensates for the wear of the rail 5 by using the same holes and fastenings, and saves the necessity of plugging the tie and forming new holes.

In Fig. 3 it will be noticed that the top 10 surface of each projection inclines slightly downward toward the rail bearing surface for the purpose of affording the proper bearing to the head of the spike.

By reason of the outer walls of the projections converging outwardly from points 15 at least opposite the spike opening through the projections, the width of the projection will be less than the width of the head of a spike driven through the opening. By this shaping of the projection a claw-bar 20 or the like may be inserted beneath the sides of the spike head overlapping the sides of the projection, and the spike drawn by the claw.

I claim:

25 1. A tie plate, pressed from a single piece of material, having a shoulder and a projection, and a spike opening formed through said projection converging and meeting each other 30 at an angle, and projecting rearwardly beyond the opening so that when a spike is driven through the opening in said projection the head of the spike will extend over at least a portion of the outer walls of said projection, for the purposes stated.

2. A tie plate pressed from a single piece of material and provided on its top surface on each end with a shoulder and spike bracing 40 projections formed integral with said shoulder, there being spike openings formed through said plate on one end, away from the rail-bearing line of the shoulder, and on the opposite end projecting inwardly beyond the rail-bearing line.

45 3. A tie plate pressed from a single piece of material having a rail-bearing shoulder arising from one end of said plate and a rail-

bearing projection arising from the opposite end of said plate, there being spike openings formed through said plate outwardly 50 from the rail-bearing line of the first mentioned shoulder, and spike openings formed through the other end of said plate inwardly beyond the rail-bearing line of said last mentioned shoulder, whereby said plate may be 55 reversed and the position of the shoulder reversed relative to the inside and outside edge of the base of the rail.

4. A tie plate pressed from a single piece of material and provided with a series of 60 projections at each end, said projections being staggered relative to each other, and a shoulder formed integral with each row of projections, said plate being provided with a number of spike openings disposed in different positions laterally relative to the rail-bearing line in order to accommodate rail bases of different widths.

5. A tie plate provided on its top surface with two oppositely formed shoulders, a series of projections formed integral with said shoulders, there being spike openings formed through said plate operating from the rail-bearing line of one of said shoulders, and spike openings formed through said plate 70 inwardly beyond the rail-bearing line of one of said shoulders, whereby said plate may be reversed and reapplied to the tie by using the original openings and fastenings.

6. A tie plate having formed thereon a series of projections, the inner walls of which form two rail-bearing lines, there being spike openings formed through some of said projections away from the inner walls thereof, and spike openings formed through 85 said plate extending partially beyond the inner walls of some of said projections.

In testimony whereof, I have signed my name to this specification, in presence of two subscribing witnesses.

EDWARD L. ADREON, JR.
